GARTER

George C. Mason, Madison, N. C., assignor to
Gem-Dandy, Inc., Madison, N. C.

Application July 10, 1946, Serial No. 682,622

3 Claims. (Cl. 2—314)

1

This invention relates to a garter construction, and more particularly to that type of garter including a leg encircling elastic leg band, and means for connecting a hose engaging pendant thereto.

An important object of the invention is to provide a connection between the leg band and hose engaging pendant, including a plate, the connection between the pendant and plate being such that the pendant may pivot towards and away from the leg of the person wearing the garter, but will be restricted against sidewise movement with respect to the plate, whereby the tension of the leg band acts to swing the pendant out of a vertical position and draw the free end of the pendant upwardly, thereby increasing the tension on the hose with which the garter is connected, without increasing tension and leg gripping action of the elastic leg band of the garter.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing:

Figure 1 is an elevational view of a garter constructed in accordance with the invention.

Figure 2 is a fragmental elevational view illustrating the position which the pendant assumes, when the leg band is stretched around the leg of the person wearing the garter.

Figure 3 is a sectional view taken on line 3—3 of Figure 1.

Referring to the drawing in detail, the garter includes a plate 5, which is constructed of any desirable sheet material, such as metal, plastic or the like, the plate having an upper slot 6 extending transversely thereof, forming a bar 7.

Disposed longitudinally of the plate 5 are slots 8, which provide a central bar 9 that is pressed outwardly from the plate, so that the elastic band 10, which forms a part of the garter and which encircles the leg of the wearer, may be positioned thereunder in such a way as to secure the plate to the band, without the necessity of stitching.

One end of the plate is reduced and bent inwardly, providing a bearing 11 at the lower end of the plate, the bearing 11 accommodating one end of the button loop member 12, as clearly shown by Figure 3 of the drawing, thereby pro-

2

viding a connection between the button loop member 12 and the plate 5, which will permit free swinging movement of the button loop member towards and away from the leg of the person wearing the garter but restrict lateral swinging movement in a plane with the planes of the side faces of the plate 5.

The reference character 13 indicates the button tape of the garter to which the button 14 is secured, the button 14 cooperating with the button holding member 12 securing the hose thereto.

Formed on the bar 9 adjacent to the upper end thereof, is the stud 15 over which the eye member 16 secured at one end of the member 10, is positioned, in securing the elastic band around the leg of the wearer.

From the foregoing it will be seen that since the stud 15 is disposed adjacent to the upper end of the bar 9, the plate 5 will be tilted or swung to the position as shown by Figure 2 of the drawing, when the eye member 16 is positioned over the stud 15, thereby increasing the tension on the hose without increasing tension and the leg gripping action of the elastic band of the garter.

Having thus described the invention, what is claimed is:

1. A garter comprising a rigid plate to which one end of an elastic leg band is secured, the leg band being extended from one side edge of the plate, a stud on the plate disposed above the longitudinal center of the plate, an eye member secured to the other end of the leg band, and pivotally engageable by the stud, whereby the lower end of the plate is swingable laterally, a sleeve bearing member of rigid material integrally formed with the lower edge of the plate and extended transversely of the plate, and a hose-engaging loop member carried by the bearing member, the portions of the loop member projecting from the ends of the bearing member being bent, whereby to prevent lateral movement of the loop member relative to the bearing member and the plate.

2. A garter comprising a rigid plate to which one end of an elastic leg band is secured, a stud on the plate disposed above the longitudinal center thereof, an eye member secured to the other end of the leg band, and pivotally engageable by the stud, whereby the lower end of the plate will swing laterally, a bearing member of rigid material integrally formed with the plate, and a hose-engaging loop member connected to the bearing member for lateral swinging movement therewith and with the plate.

3. A garter comprising a rigid plate to which

one end of an elastic leg band is secured, the leg band being extended from one side edge of the plate, a stud secured to the plate adjacent the upper end and intermediate the side edges thereof, a bearing member rigidly joined to the plate at the lower end thereof, a rigid loop member supported directly within the bearing member for lateral swinging movement therewith, the loop member being extended downwardly from the plate in alignment with a line drawn longitudinally through the center of the plate, and an eye member secured to the other end of the leg band and pivotally receivable by the stud, whereby the plate, bearing member, and loop member are laterally swingable.
